GOLF TRAINING DEVICE

Chester T. Hanley, Chicago, Ill.

Application November 23, 1933, Serial No. 699,359

5 Claims. (Cl. 273—35)

The present invention relates to a new and improved device for training golf players in the correct execution of the golf swing.

The primary objects of the invention reside in the provision of a novel golf training device which acts, through the application of a yieldable force on the left wrist and forearm of the golf player, to urge these members into the correct positions for the proper execution of the back stroke, the down-stroke and the follow-through, constituting the components of a good golf swing, and through practice to establish the suggested muscle action as a habit so as to confirm the player in the correct essentials of the swing.

Another object of the invention is to provide a device of the foregoing character which is simple and inexpensive in construction, which is capable of being easily and quickly applied, and which does not detract from the pleasure of the game.

Further objects and advantages will become apparent as the description proceeds.

In the accompanying drawing, Figure 1 is a view of a device applied to the left arm of a player, and embodying the features of my invention.

Fig. 2 is an enlarged view of the device.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The execution of a correct golf swing is generally recognized as involving the application of certain fundamental principles. Thus, the left arm of the player should be held as straight as practicable. The wrists should be cocked or bent upwardly during the latter portion of the back stroke. During the down stroke, the wrists should remain cocked until the club head is about to hit the ball. Straightening of the wrists when the club head is in the hitting zone results in a substantial increase in distance through which the ball is projected. After the ball has been hit, the arms and hands should follow through, and at the end of the follow through stroke, the wrists should again be cocked.

Most students learning to play golf understand these principles, but have great difficulty in applying them consistently. Their muscles are not trained. In attempting to remember and exe-

cute the different things that should be done in various stages of the golf swing, they become confused, and hence lose their timing and co-ordination.

To overcome these difficulties, the present invention contemplates the use of a mechanical device which is applied to the left arm, and which, through a properly directed yieldable force, tends to suggest, remind or urge the muscles to perform the proper actions without undue exercise of the mental faculties. To this end, the preferred form of device illustrated in the drawing comprises a yieldable tension member 10, preferably in the form of a band of elastic webbing, which is anchored at one end to the left arm and at the other end to the left hand in such a manner that it tends to cock the left wrist laterally toward the thumb side.

Any suitable means may be provided for attaching one end of the band 10 to the arm. In the present instance, one end of the band 10 is attached to a loop 11 adapted to encircle the arm, preferably just above the elbow. The loop, even though comparatively loose, is held against sliding along the arm by the elbow, and at this point does not affect the blood circulation or muscle action. The loop 11 may be formed by securing the inner end of the band 10 to an intermediate portion thereof. As illustrated, the inner end of the band 10 is threaded through a loop fastener 12, then is folded back along its length, and then is connected to an intermediate portion of the band by means of a slideable buckle 13. The fastener 12 is adapted for interlocking engagement with a suitable button 14 riveted to the band 10 to complete the loop 11 after the band has been wound about the arm.

The outer end of the band 10 likewise may be attached in any suitable manner to the hand, as for example, by means of a member 15 enclosing the palm. Preferably, the member 15 is a fingerless glove. The outer end of the band 10 is threaded through a loop fastener 16, and is then folded back along its length and connected to an intermediate portion of the band by means of a slideable buckle 17. A suitable button 18 riveted to the glove 15 approximately between the thumb and the forefinger is adapted for interlocking engagement with the fastener 17 to complete the connection. The band 10 when attached to the glove 15 extends underneath the thumb and along the inside of the forearm so as to impart a lateral inward pull on the hand. It will be understood that by sliding either or both of the buckles 13 and 17 along the band 10, the

length of the latter can be adjusted to the proper size for each user.

When addressing the ball, it is comparatively easy and natural to hold the left arm and wrist straight even though a slight pull is exerted by the band 10. On the back stroke, the pull of the band 10 tends to cock both wrists, and serves to prevent the wrists from rotating before and after being cocked. Thus, the wrists are retained in the correct position, and are naturally cocked at the end of the back stroke without requiring special mental effort. The pull of the band 10 also serves to prevent the wrists from straightening at the top of the back stroke and during the initial portion of the down stroke. However, just before impact, the natural effort to hit the ball causes an instinctive straightening of the wrists, thereby giving the desired snap to the blow at the critical time.

20 Confining the elbows and wrists to their correct positions during the back and down strokes, causes the club head when approaching the ball to follow an arc inside that of the back stroke and enables the player to execute a good follow-through stroke. The pull of the band 10 tends to cock the wrists at the end of the follow-through stroke. While the pull of the band 10 tends to cock the wrists, it also tends to set up an instinctive mental tendency to avoid bending 25 of the left elbow during the back and down strokes.

Use of the device in play serves to train the muscles to perform a correct golf swing. After 30 a time, the correct movements become a confirmed muscular habit. The device is applied to the left arm as illustrated for right handed players. It will be understood, that the device may also be adapted for left handed players, and in this event, it is applied to the right arm.

I claim as my invention:

1. A golf training device comprising an elongated yieldable tension member, means for removably securing one end of said member to one upper arm of a player, and means to secure the other end of said member to the corresponding hand, whereby said member exerts a pull tending to cock the wrist laterally. 5

2. A golf training device comprising an elongated yieldable tension member, means for removably securing one end of said member to the left upper arm of a player, and means to secure the other end of said member to the left hand, whereby said member exerts a pull tending to 10 cock the left wrist laterally. 15

3. A golf training device comprising an elongated elastic strap, one end of said strap being adapted to be wrapped about one upper arm above the elbow of a player and then secured to an intermediate portion of said strap, and a glove 20 for the corresponding hand, the other end of said strap being adapted to be attached to said glove approximately between the thumb and the forefinger to exert a lateral pull on the hand. 25

4. A golf training device comprising an elongated elastic strap, one end of said strap being adapted to be wrapped about one arm of a player and then secured to an intermediate portion of said strap, means for encircling the player's hand, and means for attaching the other end of said 30 strap to said last mentioned means. 35

5. A golf training device comprising means adapted to be attached to one upper arm of a player, means adapted to be attached to the player's corresponding hand, and an elongated member connecting said means and tending to exert a lateral pull on the hand.

CHESTER T. HANLEY.
